UNITED STATES PATENT OFFICE.

HARRY L. BEACH, OF COSHOCOTON, OHIO.

DESIGN FOR A SHELF.

No. 38,203.

Specification for Design.

Patented Aug. 28, 1906.

Application filed July 3, 1906. Serial No. 324,709. Term of patent 14 years.

To all whom it may concern:

Be it known that I, HARRY L. BEACH, a citizen of the United States, residing at Coshocton, in the county of Coshocton and State of Ohio, have invented a new, original, and ornamental Design for a Shelf, of which the following is a specification.

In the accompanying drawings, forming a part of this specification, Figure 1 is a perspective view of the shelf. Fig. 2 is a perspective view of said shelf reversed.

I claim—

The ornamental design for a shelf, as shown.

HARRY L. BEACH.
